REMOTE CONTROL FOR RADIO APPARATUS

George L. Beers, Collingswood, N. J., assignor to
Radio Corporation of America, a corporation
of Delaware

Application April 25, 1933, Serial No. 667,774

8 Claims. (Cl. 250—20)

The present invention relates to radio receivers and more particularly to control systems therefor.

One of the main objections to known remote control systems for radio receivers is that the added cost which is entailed thereby is often excessive and prohibitive to commercial use of such systems. Accordingly, it is an object of my invention to provide a remote control system for a radio receiver, which does not add greatly to the cost of the receiver.

Another object of my invention is to provide an improved receiver which permits remote control of tuning and other functions of the same without added complication and excessive cost characteristic of known receiving systems and receivers embodying such control.

More specifically, an object of my invention is to provide a superheterodyne receiver so designed that a portion of the superheterodyne circuit and associated apparatus forms a remote control unit which may be utilized as a unitary part of the receiver, or which alternatively, may be connected as a remote control unit, to the main unit of the receiver by a cable.

A further object of my invention is to provide a receiver of the above-mentioned character in which the remote control unit may be combined with the main receiver unit to form a receiver of conventional appearance to be operated in the conventional manner.

A still further object of my invention is to provide a remote control unit of the above-mentioned type, in which a minimum number of conductors are required in the remote control cable to effect a desired high degree of control and efficient operation of the receiver.

Other features and advantages of my invention will appear from the following description when taken in connection with the accompanying drawings, in which

Figure 1 is a circuit diagram of a radio receiver embodying my invention;

Fig. 2 is a front view of my radio receiver showing the remote control unit positioned within the main unit to form a conventional receiver;

Fig. 3 is a perspective view showing the receiver arranged for remote control, the two receiver units being connected by a cable;

Fig. 4 is a plan view, partly in section, of the receiver of Fig. 1 showing how the remote control unit and the main unit are connected by a cable; and

Fig. 5 is a plan view similar to Fig. 4 illustrating a modified form of my invention.

Referring to Fig. 1, the embodiment of the invention illustrated comprises a superheterodyne receiver which is divided into two portions, a remote control portion 10 which is shown enclosed in the dotted rectangle 11, and a main receiver portion 12 which is shown enclosed in the dotted rectangle 13. These two portions of the receiver are connected by a cable 14.

The remote control unit 10 includes a radio frequency amplifier tube 15 and another tube 16 which functions both as an oscillator and the first detector. The main receiver unit 12 includes intermediate frequency amplifier tubes 17 and 18, an automatic volume control tube 19, a second detector, indicated at 20, an audio amplifier indicated at 21, and a power supply unit indicated at 22.

Considering the circuit in detail, an antenna or signal source 23 is connected to the primary 24 of a shielded transformer 26 located in the main receiver unit 12. The secondary 27 of the transformer 26 is coupled to the primary 28 of a radio-frequency transformer 29 in the remote control unit 10 by means of a coupling condenser 30 and a cable lead 31. The radio frequency connection through the primary winding 28 is completed through a condenser 32 which connects the lower end of winding 28 to ground.

The secondary 33 of the radio frequency transformer 29 is shunted by a variable condenser 34 and a by-pass condenser 36 in series. The condenser 34 tunes the secondary circuit to the desired radio frequency, the capacity of condenser 36 being so large that it has but little effect on the tuning.

The radio frequency amplifier tube 15 is preferably of the screen-grid type and comprises a heater 37, an indirectly heated cathode 38, a control grid 39, a screen grid 40, a suppressor grid 41, and an anode 42. The suppressor grid 40 is mainly for the purpose of preventing secondary-emission from the anode.

The tunable secondary circuit of the radio frequency transformer 29 is connected to the control grid 39 through a lead 43. It is connected to the cathode 38 through ground and through a biasing resistor 44 shunted by a condenser 46, this resistor with its variable tap 47 forming a sensitivity control for the receiver, as well as supplying the proper grid bias.

A biasing potential is supplied to the control grid 39 over the same cable conductor 31 to which the antenna 23 is coupled. This grid biasing connection may be traced from the biasing resistor 48 in the automatic volume control cir-

cuit, through the conductor 49, the high resistance unit 50, through the conductor cable 31, the primary winding 28, the resistor 51, and through the secondary winding 33 to the control grid 39. 5 The biasing resistor 48 is shunted by a condenser 45 of the proper capacity to give the resistance and capacity combination a time constant such that audio frequencies will not be impressed on the grids of the tubes which are 10 biased for automatic volume control by the resistor 48.

The resistor 51, which has a value of the order of 500,000 ohms, and the condensers 32 and 36 15 form a filter which filters the hum induced in the lead 31 by the filament heater current to keep it from being impressed on the grid of tube 15.

The vacuum tube 16 includes the grid and plate elements of both an oscillator and a first detector, these elements having a common cathode 52 and heater element 53. The oscillator elements consist of the control grid 54 and the grid or plate element 55. 20

The first detector elements consist of the control grid 56, the screen grids 57, and the plate 58. 25

The output of the radio frequency amplifier 15 is coupled to the first detector through a radio frequency transformer 59 which has its secondary 60 tuned by a variable condenser 61. 30 A certain amount of capacity coupling is provided by means of an open-ended winding 62.

The tuned secondary winding 60 is connected to the control grid 56 through a lead 63. It is connected to the cathode 52 through ground and 35 through a biasing resistor 64 which is shunted by a by-pass condenser 66.

The screen grids 40 and 57 of the tubes 15 and 16 are supplied with a positive direct-current potential by the power supply unit 22 through a 40 circuit which may be traced from the power supply resistor 67 through the lead 68, the cable conductor 69, the conductor 65, the resistor 70, the lead 71 to the screen grids 57, and the conductors 72 and 73 to the screen grid 40.

The plate 42 of tube 15 is connected to the plate supply conductor 65 through the primary winding of the transformer 59, while the plate 58 of the tube 16 is connected to the conductor 65 through an inductance coil 74. 45

The heaters 37 and 53 of the tubes 15 and 16, respectively, are connected in series and supplied with current by a transformer 76 connected to the alternating-current line. The heater circuit may be traced from the secondary winding 55 of transformer 76 through the conductor 77, the cable conductor 78, the filament 37, the filament 53, to ground. In order to keep heater current through the cable conductor 78 at a low value, the tubes have 6 volt heater filaments. The 60 tubes in the main section of the receiver have 2.5 volt alternating current heater filaments connected in parallel.

The oscillator is of the type which has a plate coil 79 coupled to a tuned grid coil 80, the plate 65 55 being connected to the high potential lead 65 through the plate coil 79. The control grid 54 is connected through a lead 81 to the grid coil 80 which is tuned by a variable condenser 82 and a fixed condenser 83 connected in series 70 and shunted across the coil. The junction point of the condensers 82 and 83 is connected directly to ground, while the lower end of the coil 80 is connected to ground through a grid-leak resistor 84. The variable condenser 82 is employed to 75 vary the frequency of the oscillator.

The oscillator is coupled to the first detector by virtue of the fact that the electrodes of the oscillator and first detector are in the same electronic stream.

The intermediate frequency amplifier tube 17 5 is of the screen grid type having a heater element 86, a cathode 87, a control grid 88, a screen grid 89, a suppressor grid 90, and an anode 91. The control grid 88 is negatively biased by means of a connection through the grid resistor 92 and 10 the conductor 93 to the grid biasing resistor 48 in the volume control circuit, and also by means of resistor 105 in the cathode circuit.

The input circuit of the intermediate frequency amplifier 17, which is tuned to the intermediate 15 frequency output of the first detector, comprises an inductance coil 94 shunted by two condensers 96 and 97 connected in series. The upper terminal of the inductance coil 94 is connected to the control grid 88 of the amplifier tube 17 20 through a condenser 98. The lower terminal of the inductance coil has a low impedance radio-frequency connection to the cathode 87 through a circuit which may be traced through the conductor 99, the cable conductor 69, the conductor 65, the condenser 100, and through ground and the by-pass condenser 101 (shunting biasing resistor 105) back to the cathode 87. 25

The output circuit of the first detector is coupled to the input of the intermediate frequency 30 amplifier 17 through two circuits tuned to the intermediate frequency and coupled by a condenser 97, common to the two circuits. The first tuned circuit may be traced from the plate 58 35 of the first detector tube, through a tuning condenser 102, the lead 103, the cable conductor 104, the connection 106, through the condenser 97, through the connection 99, the cable conductor 69 and the conductor 65 to the lower end of the inductance coil 74, and through coil 74 back to 40 condenser 102. It will be noted that the cable conductor 69 serves both as a coupling conductor for the intermediate-frequency circuit and as a plate supply lead for the tubes 15 and 16. 45

The second tuned circuit is the one comprising inductance coil 94 and condensers 96 and 97.

It will be apparent that the capacity between the cable conductors 104 and 69 is in shunt to the condenser 97, and will have some effect upon the tuning of the circuits. It is desirable to make 50 this effect negligible because it is difficult to obtain cables having uniform capacity between conductors, and also because it may be desired to use various cable lengths. This is accomplished both by using the specific type of coupling described 55 above and by making the capacity of condenser 97 very large compared with the capacity between conductors 104 and 69.

For example, in an embodiment of my invention, using an intermediate frequency of 175 kilocycles, the following values may be employed: 60 condenser 97—5000 micro-microfarads; condenser 96—175 micro-microfarads; condenser 102—175 micro-microfarads; capacity between conductors 104 and 69—approximately 400 micro-microfarads. 65

The above-described scheme for coupling the output circuit of the first detector to the input circuit of the intermediate amplifier was employed after various coupling circuits had been tried 70 without success. For example, it was found that inductive coupling could not be employed because the cable capacity was in shunt to the coupling coil and formed a resonant circuit therewith. This resonant circuit introduced an undesired 75

peak in the selectivity curve of the coupling circuit, and, in general, made it impossible to give the coupling circuit the proper selectivity characteristics. No such difficulty is encountered when using the coupling circuit shown in Fig. 1, since there is no third resonant circuit. By employing such a coupling circuit, the two tuned circuits can be given critical coupling and the desired flat-topped selectivity curve obtained.

10 The plate 91 of the intermediate frequency amplifier tube is connected to the resistor 67 of the power supply unit through a conductor 107, the primary 108 of a tuned intermediate-frequency transformer, and a conductor 109. The secondary 15 110 of the tuned transformer is connected to the input circuit of the second detector 20. The output of the second detector 20 is supplied to the audio amplifier 21 through an audio transformer 111, and from the audio amplifier 21 to a loud-speaker 112 through an output transformer 113.

15 Manual volume control is provided at the remote control unit 10 by means of a potentiometer 114 which is shunted across the output of the second detector 20 through cable conductors 117 and 118. The upper terminal of the primary of the audio frequency transformer 111 is connected to a variable tap 116 on this potentiometer through cable conductor 115.

20 Automatic volume control is provided by means of tubes 18 and 19, tube 18 being a screen grid tube having a heater element 119, a cathode 120, a control grid 121, a screen grid 122, a suppressor grid 123, and an anode 124, and tube 19 being a rectifier tube comprising a heater element 126, 25 a cathode 127, and an anode 128.

25 The control grid 121 of tube 18 is connected, through a coupling capacity 129, to the upper terminal of the inductance coil 94 in the tuned intermediate frequency circuit. It is biased 30 through high resistance 130 and a biasing resistor 131 which is shunted by a by-pass condenser 132. The screen grid 122 of the volume control tube 18, as well as the screen grid 89 of the intermediate frequency amplifier tube 17, is connected to the 35 resistor 67 of the power supply unit through a conductor 133. The plate 124 of tube 18 is connected to the power supply resistor 67 through the primary 134 of a transformer 135, which feeds the output of tube 18 to rectifier tube 19.

40 The upper terminal of the secondary 136 of this transformer is connected to the plate 128 of the rectifier tube 19. The lower terminal of the secondary 136 is connected through a biasing resistor 45 48 to ground, and from ground through the lower section 137 of the power supply resistor 67 and through a conductor 138 to the cathode 127 of the rectifier tube.

45 The lower section 137 of the resistor 67 is included in series with the biasing resistor 48 in order to give a delayed volume control action.

50 Referring to Figs. 2 and 3, the portion of the apparatus shown enclosed in rectangle 13 in Fig. 1 is mounted in the cabinet 140, the loudspeaker 112 being mounted in the lower part behind a grille 141. The upper part of the cabinet has a panel 142 in the front thereof, which may be concealed by means of two doors 143.

55 The panel 142 has an opening or recess therein for the reception of the remote control unit 10 which is mounted in a small cabinet 144 having a front panel 146 carrying part of the receiver controls. These controls are the sensitivity control 147 (tap 47 in Fig. 1), the tuning control 148 (connected to the three ganged condensers)

mounted underneath the tuning dial 145, and the volume control 149 (tap 116 in Fig. 1).

Two controls are mounted on the panel 142 of the main cabinet, these being a tone control knob 150 for low frequency response, and a tone control knob 151 for high frequency response.

60 As shown in Fig. 2, the remote control unit 10 may be placed in the opening in the panel of the main unit, with the panel 146 of the remote control unit flush with the panel 142 of the main unit to form a receiver of substantially conventional appearance. Or, if desired, the remote control unit 10 may be pulled out of the main cabinet and placed on a stand and the two units connected together by means of the cable 14 as 65 indicated in Figs. 3 and 4, so that the main unit of the radio receiver may be operated from a remote point.

65 As shown in Fig. 4, there is preferably a plug 153 mounted on the back of the remote-control 20 unit 10 and a plug socket 154 so mounted on the main receiver unit 12 that, when the remote-control unit is moved into position in the panel opening, the plug 153 and socket 154 engage automatically. In the specific arrangement illustrated 25 in Fig. 2, the cable 14 can be plugged into the socket 154 at the rear, while the remote-control unit is plugged in at the front. For remote control, the remote-control unit 10 is pulled out of the opening and plugged into the cable socket 30 155.

70 As shown in Fig. 3, a door 156, hinged at its upper edge, may be mounted inside the opening of the panel 142 and so arranged that when the remote control unit 10 is removed, the door will 35 drop down by gravity or spring action to close the panel opening. If such a door is provided, it may be desirable to omit the doors 143.

75 Instead of using an arrangement in which the cable 14 is plugged into the back of the remote control unit when the remote control feature of the receiver is to be utilized, it may be desirable to employ the arrangement shown in Fig. 5. In this arrangement the cable 14 is permanently connected to the remote control unit 10 and is 40 wound up on a reel 157 which operates the same as a window shade roller. A cable pig-tail connection 158 is provided between the reel and the receiver circuit.

80 Obviously, the location of the recess for the remote control unit is not restricted to the front panel of the main unit. It may be in the top of the main unit or it may be at the upper front edge of the large cabinet in the form of a "notch" in the cabinet edge.

85 Various other modifications may be made in my invention without departing from the spirit and scope thereof, and I desire, therefore, that only such limitations shall be placed thereon as are necessitated by the prior art and are set 60 forth in the appended claims.

55 I claim as my invention:

1. In a radio receiver circuit, a radio frequency transformer having a primary winding and a secondary winding, an electric discharge device 65 having input electrodes connected to said secondary winding, a source of signals connected to said primary winding, a high impedance unit, said secondary winding being connected at one terminal end only through said high impedance 70 unit to one terminal end only of said primary winding, said terminal ends being above ground at a direct current potential, and a common circuit lead for transmitting both a signal current from said source and a biasing potential through 75

said primary winding connected to the opposite terminal end of the primary winding.

2. A superheterodyne receiver comprising a remote-control section and a main section, said remote-control section including a radio frequency amplifier tube, an oscillator, and a first detector, said main section including an intermediate frequency amplifier and a second detector, a cable including a plurality of conductors for electrically connecting said two sections, a source of biasing potential in said main section, a radio-frequency transformer having a secondary connected between the control grid and cathod of said radio-frequency amplifier tube, the connection to said grid being conductive, and a conductive connection between said source of biasing potential and said secondary whereby said grid is biased, said connection including one of said cable conductors, an antenna coupled to a point on said last-named conductive connection at said main section, and a high impedance connected in series with said conductor between said source of biasing potential and said point.

3. In a radio receiver, a main unit including at least a portion of a tuned circuit comprising an inductor and a capacitor, a remote control unit including at least a portion of a second tuned circuit comprising an inductor and a capacitor, and means for transferring signal energy from one of said units to the other of said units, said means comprising two adjacent conductors which have substantial capacity between them and a coupling capacitor which is connected in series with said first inductor and said first capacitor to complete said first tuned circuit and which is also connected in series with said second inductor and said second capacitor to complete said second tuned circuit, said coupling capacitor also being in parallel with the capacity between said conductors and being of a value to provide critical coupling between said tuned circuits.

4. A radio receiver having a portion of the electrical units installed in a cabinet and having another portion of the electrical units installed in a portable remote-control box, said other portion including the tuning elements of the receiver, and means for electrically coupling said two portions, said means comprising two coupled circuits, each including reactance units and both tuned to the same frequency and at least one of them including two parallel conductors which have capacity between them, the means for coupling said two tuned circuits comprising a reactance common to said tuned circuits, said common reactance being connected in series with the reactance units of each tuned circuit and consisting of the capacity between said conductors and a condenser having a substantially larger capacity than the capacity between said conductors.

60 5. A radio receiver comprising a main unit and a remote-control unit, said remote-control unit including means for converting a radio frequency signal to an intermediate frequency signal, said main unit including means for converting said intermediate frequency signal to an audio frequency signal, and coupling means for transferring the intermediate frequency output of said

remote-control unit to the intermediate frequency input circuit of said main unit, said coupling means comprising two circuits each of which is tuned to said intermediate frequency, said circuits being coupled by a capacity which is common to said two circuits and which is serially connected in each of said circuits.

6. A radio receiver comprising a main unit and a remote-control unit, said remote-control unit including means for converting a radio frequency signal to an intermediate frequency signal, said main unit including means for converting said intermediate frequency signal to an audio frequency signal, and means for transferring said intermediate frequency signal from said remote-control unit to said main unit, said means comprising two coupled circuits, each of said circuits being tuned to said intermediate frequency and including two parallel conductors which have substantial capacity between them, the means for coupling said two tuned circuits comprising a reactance common to said tuned circuits, said reactance consisting of the capacity between said conductors and a condenser having a substantially larger capacity than the capacity between said conductors, said common reactance being serially connected in each of said tuned circuits.

7. A radio receiver comprising a main unit and a remote-control unit, said remote-control unit including means for converting a radio frequency signal to an intermediate frequency signal, said main unit including means for converting said intermediate frequency signal to an audio frequency signal, and means for transferring the intermediate frequency output of said remote-control unit to the intermediate frequency input circuit of said main unit, said transferring means comprising two capacity-coupled tuned circuits which include cable conductors, one of said tuned circuits being completely contained in one of said units, except for the capacity between said conductors, and the other of said tuned circuits including at least one reactance element located in the other of said units and also including said cable conductors, the capacity which couples said tuned circuits being serially connected in each of said circuits.

8. Radio apparatus comprising a main unit and a remote-control unit, a cable including a plurality of conductors for electrically connecting said units, one of said units including an inductance coil shunted by two condensers connected in series and tuned by said two condensers to a certain frequency, the other of said units including a tuning coil, one terminal of said tuning coil being connected to the junction point of said two condensers through a tuning condenser and one of the conductors of said cable, the other terminal of said tuning coil being connected to the other terminal of one of said two condensers by means of another of the conductors of said cable, the capacity of said one condenser being several times as great as the capacity between said two cable conductors, said tuning coil, said tuning condenser, and said one condenser forming another resonant circuit tuned to said certain frequency.

GEORGE L. BEERS.
